ALFRED J. WILLEY AND FORREST H. VAUGHN, OF HAMMOND, INDIANA.

TYPEWRITER-PAPER SUPPORT.

Application filed June 30, 1924. Serial No. 723,346.

This invention relates to a typewriter paper support and has for its primary object the combination of an auxiliary support with a main paper feed mechanism of a typewriter so that a continuous strip of paper may be fed through the typewriter so as to prevent loss of time in continuous typewriting.

An object of the invention is the construction of a support capable of feeding a continuous strip of paper around the typewriter roller for making continuous records.

A feature of our invention is the substantial inexpensive manner in which the parts are connected together and to the typewriter so that the roll of paper will be properly supported and may be readily renewed.

With these and other objects in view the invention will be better understood from the following detailed description taken in connection with the accompanying drawing wherein:

Fig. 1 is a plan view of our invention shown attached to a portion of a typewriter.

Fig. 2 is a rear elevation.

Fig. 3 is a sectional view on the line 3—3 of Fig. 1.

Fig. 4 is a sectional view on the line 4—4 of Fig. 1.

Fig. 5 is a sectional view on the line 5—5 of Fig. 1.

Again referring to the drawing illustrating one of the many constructions of our invention our improved typewriter paper support comprises a pair of arms 1 and 2 which have one end pivotally connected to the typewriter as indicated at 3. These arms may have upwardly swinging movement and to support the same in horizontal position they are supported on the rest 4. Mounted on the ends of the arm are the clips 5 to one of which is pivotally connected one end of the rod 6 and the other end of this rod is forked to straddle the clip in

its locked position by the set screw 7 that 45 also binds against the arms for locking the clip in position. A similar set screw 8 is mounted in the other clip and binds against the arm. A roll of paper 9 is mounted on the rod and is fed forwardly and then 50 around the typewriter roll 10. Thus it will be seen that a continuous strip of paper is provided so that the typewriter may be continuously used without periodic changing of the paper.

For the purpose of accurately supporting the roll of paper in proper position and allow for any slight irregularities we provide a pair of coil springs 11 engaging against the ends of the roll and held in position by 60 adjustable bearings 12 which are mounted on the rod.

From the foregoing description taken in connection with the accompanying drawings it will be apparent that we provide a support of inexpensive construction that may be readily adjusted or disconnected and which will properly support a roll of paper for continuous feeding action.

It is, of course, to be understood that the 70 invention may be constructed in various other manners and the parts associated in different relations and, therefore, we do not desire to be limited in any manner except as set forth in the claim hereunto appended.

Having thus described our invention what we claim is:

A typewriter paper support comprising arms pivotally connected to the typewriter, a rod pivotally connected at one end to one 80 of the arms and detachably connected at the other end with the other arm, a paper roll slidably mounted on the rod, and spring devices engaging opposite ends of the roll.

In testimony whereof we affix our signatures.

ALFRED J. WILLEY.
FORREST H. VAUGHN.
